Horace Bartlett, Bridgeport, Connecticut

Letters Patent.

The subscriber referred to in these Letters Patent, and making part of the same, containing a description in the words of the said Horace Bartlett, himself of his improvement in the construction of a Bricking Stove.

Be it known that I, Horace Bartlett, of Bridgeport in the County of Fairfield, and State of Connecticut have invented a new and useful improvement in the form and construction of a bricking stove & that the following is a full and exact description of the construction & operation of the said bricking stove as invented or improved by me. The bed for the fire lies across the stove from front to rear see plate 111 letter A... A plate forming the remaining part of the bottom turning in a horizontal form from the top of this bed to the full length of the stove which for the sake of description I call the wings see plate 111. Plate A. is for the bottom of the oven over the bed for the fire or plate A.1. between these plates the flue is stopped off forming thereby a more powerful draft, through this plate over the fire, is a hole with various sized pipes, in which the common iron ware may be used, see plate 111 letter B... at each corner of this plate is a hole for the smoke, over which stands a pipe in the form of a half circle letter C... These pipes are 18 inches long forming the height of the oven... between these pipes connected with them in a circular form is a piece forming the end of the stove. Hiding these pipes is a piece forming the length of the oven, leaving an opening in the center for the smoke letter D... upon the top of these pipes, is a plate forming the top of the oven plate 111... over this is another wired kind forming what I call the oven plate A.1. Through which

at each end is a hole for boiler tubes..... from the back part of this dam, extends the pipe latterly through the bottom plate of the dam which forms the top of the oven is a hole of 15 inch diameter with a tube rising above the pipe to prevent ashes or coals from falling into the oven latterly - this conveys the steam into the dam when boiling - When baking bread the hole is closed by a damper on the underside of the plate. Between these plates, in the inside of dam are two pieces of iron to hold the boiler, to confine the heat together these two plates A & B - The heat piping around in front of the dam, from these next to the pipe, which causes more heat upon the top of the oven. Each part of these pieces around the boiler is made to slide forming the dampers, so as to be easily hung upon the pipe, opening from the center.

What I claim as new in the construction of the oven is to take eight layers of broad straw twice, placing them in two or three layers deep. To accomplish this, I claim as new the use of a sheet of iron which being a nonconductor of heat raised from the bottom of the oven on legs of wire prevent the bottom layers from burning, whilst heat is thrown sufficiently through the oven to bake the whole by changing them once or twice. This sheet ought not to cover the bottom of the oven leaving room for heat to rise around its edges. Also the hole in the bottom of the oven, for boiling, the oven being 15 inches high prevents intercepting when putting in or taking out the baking utensils. Also the tube carrying the steam through the top of the oven into the dam, thereby being below & taking heat on the line above. Also the combing the blaze into small tubes, by which the heat is conveyed with much greater strength so that not with touching the boiler on top are a distance from the fire they are safe. Also the pieces around the boiler are joined together by a wire and the wire is bent so as to be easily taken off when the boiler is to be cleaned.
